UNITED STATES PATENT OFFICE

STEVEN FTACEK, OF OTTAWA, ILLINOIS

AEROPLANE PROPELLER

Application filed February 24, 1931. Serial No. 517,972.

This invention appertains to vehicle propulsion, and more particularly to an improved propeller for use in conjunction with air crafts, such as aeroplanes, and the like.

One of the primary objects of my invention is to provide an improved aeroplane propeller, so constructed as to effectively reduce head resistance, and at the same time obtain a maximum amount of action on the air for drawing the aeroplane through the air.

Another salient object of my invention is to provide an improved propeller which will draw the aeroplane through the air with a maximum amount of speed with a minimum amount of engine revolutions, whereby the necessity of running the engine at a high rate of speed will be eliminated.

A further important object of my invention is the provision of an aeroplane propelling device embodying a propeller shaft having connected therewith at spaced points, a plurality of propeller blades, the blades being arranged at an angle to one another and gradually diminishing in length toward the front end of the propeller shaft.

A further object of my invention is the provision of a spiral lead head on the forward end of the propeller shaft, the spiral head acting as means for reducing head resistance and at the same time to draw the propeller through the air and to direct the air on the radial blade of the propeller.

A further object of my invention is the provision of novel means for mounting the blades on the propeller shaft, whereby the blades can be readily adjusted and readily removed in case of breakage.

A still further object of my invention is to provide an improved aeroplane propeller of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawing, in which drawing:

Figure 1 is a side elevation of my improved aeroplane propeller, showing certain parts thereof broken away and in section.

Figure 2 is a diametric section taken on the line 2—2 of Figure 1 looking in the direction of the arrows. 55

Figure 3 is a detail longitudinal section taken on the line 3—3 of Figure 1, looking in the direction of the arrows.

Figure 4 is a diametric section taken on the line 4—4 of Figure 1 looking in the direction of the arrows. 60

Figure 5 is a detail perspective view of the sectional cup for bracing the propeller shaft and holding a set of blades in position. 65

Figure 6 is a front elevation of the spiral tip for the propeller shaft.

Referring to the drawing in detail, wherein similar reference characters designate corresponding parts throughout the several views, the letter A generally indicates my improved device, which comprises an elongated propeller shaft S, embodying inner and outer sections 10 and 11. The section 10 may be considered as a part of the engine 70 crank shaft, and the facing ends of the sections 10 and 11 are provided with reduced threaded extensions 12 and 13, respectively. These shaft sections 10 and 11 are connected by a two part coupling 14, and the extensions 12 and 13 are threaded into the two parts of the coupling and held against rotation by the use of suitable keys 15. The two parts of the coupling 14 can be secured together by the use of suitable bolts 16 as shown. At 80 opposite diametric points, the coupling 14 is provided with threaded sockets 17 for a purpose which will be later described. 85

The propeller shaft S preferably tapers toward its leading end and this end can be provided with a reduced screw threaded extension 18, for the reception of the left hand threaded socket 19 carried by the spiral head 20 of the shaft. This spiral head 20 tapers to a point toward its extreme outer apex or leading edge and acts as means for cutting through the air to prevent head resistance and to also act upon the air for drawing the aeroplane through the air. Likewise the spiral head acts as means for deflecting the 90 95 100

air rearward against the propeller blades which will now be described.

The propeller blades are arranged in sets along the propeller shaft S and I employ 5 three or more sets of propeller blades, and in the drawing I have illustrated three sets of blades only, but it is to be understood that the number of sets of blades can be increased. The first set of blades is indicated generally 10 by the reference character 25, the second or intermediate set of blades by the reference character 35, and the third or inner set of blades by the reference character 45. The inner or third set of blades 45 are of the 15 greatest length and the inner ends of the blades are provided with reduced threaded extensions 46, which are threaded within the socket 17 of the two-part coupling member 14. If preferred, keys can be utilized for 20 holding these blades against accidental rotation.

By the construction shown in Figures 3 and 4, it is obvious that the blades can be 25 readily removed and replaced, in case the original blades become broken or cracked from any reason. As shown, the set of blades 45 embody two blades, which extend radially from the two part coupling 14, at diametrically opposite points, and these blades are 30 shaped in accordance with my improved propeller blade design.

The first or leading set of propeller blades likewise embodies two outwardly extending blades 26 arranged at diametrically opposite 35 points, and the set of blades 35 also embodies two radially extending blades 36 arranged at diametrically opposite points relative to one another. The sets of blades 25 and 35 are connected to the propeller shaft section 40 11 in the same manner and each of the means for connecting the blades in place includes a two part cup 27 for embracing the propeller shaft. The longitudinal edges of the cup 27 are provided with flanges 28, which can 45 be connected together by means of bolts 16. The sections of the cup 27 on opposite sides thereof are provided with internally threaded sockets 29 for the reception of the reduced threaded sections formed on the inner end of 50 the blades of the sets of blades 25 and 35. If desired, these blades can be keyed in place to prevent accidental rotation thereof. Likewise, after the two part cups are bolted around the shaft, keys 30 can be utilized for 55 preventing rotary as well as longitudinal movement of the cup on the shaft.

The lengths of the blades of the sets of blades gradually diminish from the rear set of blades 45 to the front set of blades 25, and 60 thus the length of the set of blades 35 are less than the length of the set of blades 45, while the length of the set of blades 25 is less than the length of the set of blades 35.

Each set of blades is arranged at a different 65 angle on the shaft from the other sets of

blades, as clearly shown in Figure 2, and these blades of the sets of blades are staggered relative to one another.

From the foregoing description, it can be seen that I have provided a novel propeller embodying a series of sets of blades arranged in stepped relation on the propeller shaft, whereby the air is successively acted upon by the sets of blades, and whereby the air is directed back on the blades by the spiral tip of the propeller shaft. 70 75

Changes in details may be made without departing from the spirit or the scope of this invention, but:—

What I claim as new is:

In combination with a propeller shaft, of a spiral pointed tip connected to the leading end of said propeller shaft, the spiral of said tip extending from the very outer extremity and apex to the rear end of said tip, a series of separate sets of propeller blades arranged in spaced relation within the length of the propeller shaft for producing a continuous spiral from the very apex of the tip to the outer end of the last set of blades, each set extending at an angle to the remaining sets, the length of the blades of the various sets gradually increasing from the forward to the rear end of said propeller shaft, the outer ends of the various sets of blades terminating on an angle line constituting a substantial continuation of the angle of the edges of the spiral pointed tip to provide an elongated tapering spiral pulling means due to the location, length and assembly of the various blades, this spiral pulling means extending from the very apex of said spiral pointed tip to the outer ends of the last set of blades carried by the said propeller shaft. 80 85 90 95 100 105

In testimony whereof I affix my signature.
STEVEN FTACEK.
